UNITED STATES PATENT OFFICE

NOBLE M. JOHNSON, OF DETROIT, MICHIGAN

INTERNAL-COMBUSTION ENGINE

Application filed December 17, 1927. Serial No. 240,712.

This invention relates to improvements in internal combustion engines. It is an object of the invention, among other things, to provide an internal combustion engine wherein a substantially elliptical cam, fixed on a shaft, is rotated in an enclosed casing by piston rods extending inwardly from a plurality of radially arranged cylinders; wherein the piston rods are so positioned that their centre lines pass substantially through the centre of the cam at right angles to its axis, so that force exerted by the rods is transmitted directly onto the cam; and wherein valve plates are fixed on the shaft, one on each side of the casing, so that their inner surfaces bear against inlet and exhaust ports in the sides of the cylinders to regulate the flow of mixture into and from the latter.

Having thus briefly outlined the major purposes of the invention I will now describe two preferred embodiments thereof with the aid of the accompanying drawings, in which:

Figure 1 illustrates a side elevation of the invention, parts being broken away.

Figure 2 is a section on the line 2—2 of Figure 1.

Figure 3 is an enlarged detail of the cam and piston rod connection.

Figure 4 is a sectional elevation of a modified construction.

Figure 5 is a section on the line 5—5 of Figure 4.

Figure 6 is an enlarged view of the cam used in the modified construction, and

Figure 7 is a section on the line 7—7 of Figure 6.

Referring to Figures 1, 2 and 3 of the drawings, 1 designates a plurality of substantially radially arranged cylinders the inner ends of which are secured to the periphery of a casing 2 which is intended to contain a lubricant. In the cylinders 1 are pistons 3 having rods 4 thereon which project through openings 5 in the casing and terminate at their outer ends in bifurcations 6, 7 indicates a shaft which projects through both sides 8 of the casing substantially at right angles to the radially arranged piston rods. Fixed on the shaft 7 within the casing is an elliptical cam 9 around the margin of which an annular

flange 10 projects laterally in both directions. Between the inner ends of the bifurcations 6 rollers 11 are revolvably mounted which are adapted to bear against the outer surface 10^a of the flange 10; and inwardly projecting shoes 12 secured to the outer ends of the bifurcations ride around the inner surfaces 10^b of the flange 10. As the pistons move inwards on their working stroke the rollers 11 force the cam 9 around, and on the outward stroke of the pistons the rollers are held substantially in contact with the periphery of the cam by the shoes 12.

Through one side of the cylinders are intake ports 14 and through their opposite sides are exhaust ports 15. Each set of ports is normally closed by a valve plate 16, or 17, both of which are fixed on the shaft 7 outside the casing 2 one on each side of the latter. Annular intake and exhaust manifolds 18 and 19 are supported from the cylinders, one on each side of the latter, by spacing members 20, and bear against the outer sides of the valve plates 16 and 17. Each manifold has a passage 18^a, or 19^a, opposite each cylinder inlet port 14, exhaust port 15, and each valve plate 16, or 17, has an aperture 16^a, or 17^a, therethrough so that as the plate turns each cylinder inlet, or exhaust, port is in turn connected with its intake, or exhaust, manifold opening respectively.

On the valve plate 17 a starting gear 21 is provided to mesh with the starter pinion 22, and on the opposite valve plate 16 a weight 23 is provided to balance the weight of the gear 21.

In Figures 4, 5, 6 and 7, a modified construction is shown wherein the cam 9^a, which is usually circular, has elliptical slots 9^b and 9^c in both sides. The opposed slots 9^b are preferably of different width and depth to the slots 9^c. The piston rods 4^a and 4^b have bifurcated ends 10^a and 10^b to which shoes 12^a and 12^b are pivotally secured; the latter ride around in the slots 9^b and 9^c respectively as the cam rotates. Owing to the length of the shoes 12^a and 12^b, and the provision of rollers 25 and 25' on them which travel around in the slots, there is practically no possibility of one of the shoes leaving its slot 100.

at one of the intersections 30 and passing into the slot in which it is not intended to travel. In other respects the construction shown in these figures is the same as that shown in Figures 1, 2 and 3.

It will be noted that in both forms of construction the centre lines of the piston rods pass directly through the centre of the cam; and again owing to the casing 2, or 2^a, being enclosed the piston rod ends and the cam may operate in oil.

Moreover it is understood that the construction is subject to such modifications as fall within scope of the appended claims.

15 What I claim as my invention and desire to secure by Letters Patent is:

1. In an internal combustion engine, the combination of a plurality of cylinders substantially radially arranged, an inner casing to which the inner ends of the cylinders are secured, pistons in said cylinders, piston rods on said pistons projecting through the sides of said casing, a shaft extending through said casing at right angles to said piston rods, 25 a cam on said shaft within said casing adapted to be rotated by the movement of said pistons, said cylinders having inlet and exhaust ports in their opposite sides, intake and exhaust manifolds respectively at opposite sides 30 of said cylinders, and valve plates on said shaft one adapted to control communication between the intake manifold and said inlet ports and the other adapted to control communication between the exhaust manifold 35 and said exhaust ports.

2. In an internal combustion engine, the combination of a plurality of cylinders substantially radially arranged, a casing to which the inner ends of the cylinders are 40 secured, pistons in said cylinders, piston rods on said pistons projecting through the sides of said casing, a shaft extending through said casing substantially at right angles to said piston rods, a cam on said shaft adapted to 45 be rotated by the movement of said pistons, said cylinders having inlet and exhaust ports in their opposite sides, valve plates on said shaft the inner sides of which are adapted to bear against said port openings, inlet and exhaust 50 connections respectively at opposite sides of said cylinders and opposite said port openings against the outer sides of said plates, and the latter each being provided with an aperture therethrough adapted to connect 55 each inlet, or exhaust, connection with its inlet, or exhaust, port in turn as said shaft rotates.

NOBLE M. JOHNSON.
